UNITED STATES PATENT OFFICE.

JOSIAH L. YOUNG, OF TARRYTOWN, NEW YORK.

TYPE-WRITING MACHINE.

SPECIFICATION forming part of Letters Patent No. 289,489, dated December 4, 1883.

Application filed March 30, 1882. (No model.)

To all whom it may concern:

Be it known that I, JOSIAH L. YOUNG, of Tarrytown, Westchester county, and State of New York, have invented a new and useful 5 Improvement in Type-Writers, of which the following is a specification.

The invention relates to a type-writer so constructed that the operation is performed by moving a wheel or segment of a wheel, with 10 raised letters or characters on its edge, over the surface of the paper. Over this wheel or segment is an index-wheel, upon which are placed the letters or characters corresponding to those on the type-wheel. These wheels are 15 connected by a bevel-gear, and are moved together by an arm, which is pivoted to the center of the index-wheel. The outer edge of said wheel is provided with projections or notches, with spaces between. These spaces are numbered 20 or lettered the same as the numbers or letters on the type-wheel. By moving this arm to the letter desired on the index-wheel, and carrying it around to the delivery-post, then pressing down the lever on which the type-wheel and index-wheel are placed, the desired 25 letter is printed or impressed on the paper.

In the accompanying drawings, in which similar letters of reference indicate like parts, Figure 1 is a longitudinal view, partly in section. Fig. 2 is an end elevation, partly in section; Fig. 3, a top view.

In the drawings the frame is designated by letter A, Fig. 1.

B is a guide strip or track extending across 35 the frame A. This guide-strip is raised a little above the surface of the frame, to allow the paper C, which rests on frame A, to pass or move under it. The sides of said frame are grooved, and the ends of the guide-strip are 40 tongued, so that the guide-strip may be moved to any desired longitudinal position on the frame A. The grooves are marked D. Upon the guide-strip B is placed carriage E. This carriage moves along the guide-board B at regular spaces. These spaces or distances are regulated by a ratchet and pawl, or its equivalent, (marked F,) which catches into one of a line of perforations on the guide-strip B, (marked G.) When ratchet F is pressed, the pawl, catching 45 in the perforation, produces a leverage, which forces the carriage E to the next hole or perforation. When this movement of the carriage

is made the lever H is lifted above the paper. By repeating the pressure, the carriage E may be moved to any space or perforation on the 55 guide-strip B. These perforations are at exact distances apart. A rack-gear or other appropriate equivalent might be employed to move the carriage.

H is a lever pivoted at I to the carriage E at 60 its outer end, and perpendicular to its side is fixed the type-wheel J. The alphabet or symbols are raised upon the edge of this wheel or disk.

On the top of lever H, and at right angles to the type-wheel, is placed the index wheel or disk K. The edge of this wheel is turned upward or vertical from its plane, and is divided into projections and spaces marked a a'. These spaces are equal to the letters on the type-wheel, 70 and correspond with them. By means of bevel-gear L and L' or other connection, the type-wheel and index-wheel move together, so that the chosen letter on the index-wheel K is printed on the paper C by type-wheel J. The arm M is pivoted in the center of the index wheel 75 or disk, and is jointed, so as to be easily lifted above the projections and spaces a a', and can be moved around the disk in either direction.

In operating the machine the movable arm 80 is placed in the space marked by the letter desired to be printed. This arm (marked M) is stopped at a fixed post marked N. This post is provided with a slot, O, into which the arm M drops. The lever H is then pressed downward at the printing end and the letter delivered upon the paper. The arm M is again moved to the space desired, and brought around to the fixed post N, bringing or revolving the disk as before, which in turn, by the agency 90 of the bevel-gears, also revolves the type-wheel. The lever H is again pressed upon the paper, and the printing performed as before. After printing a letter, the pressure of the hand on lever H is slightly relaxed, which allows spring 95 P or its equivalent to lift the printing end of lever H above the surface of the paper. As it lifts, the ratchet F is operated, which instantly carries the carriage E to the next required space by means of the pawl Q, Fig. 2, 100 catching into the hole or perforation G on guide-strip B. The roller S supplies the type-wheel with printer's ink or its equivalent.

R and R' are feed-rollers on the top of frame

A, used to carry the paper longitudinally from line to line. One of these rollers, R², is placed flush with the top surface or plane of frame A. The other (marked R) is placed above it in appropriate position. The upper roller is covered or supplied with bands of rubber or other equivalent to facilitate the feeding of the paper. I also use rollers R R² as a clamp to hold paper in position when I use the grooves D to change the position of the guide-strip B.

What I claim is—

1. In a type-writer, the guide-strip B, in combination with the carriage E, type-wheel J, index-disk K, arm M, post N, with its notch O, and bevel-gears L L², substantially as described.

2. In a type-writer, the combination of the type-wheel J, index-disk K, and arm M, with the lever H and bevel-gears L and L², substan-

tially as set forth and for the purpose specified.

3. In a type-writer, the combination of the type-wheel J and index-disk K, with arm M, notched post N, lever H, and bevel-gear L L², substantially as described, and for the purpose specified.

4. In a type-writer, the combination of the type-wheel J, index-disk K, arm M, post N, with its notch O, lever H, bevel-gears L L², carriage E, ratchet F, with its pawl Q, and guide-strip B, substantially as described, and for the purpose specified.

JOSIAH L. YOUNG.
